Primary Examiner — Patricia A Palasik*(74) Attorney, Agent, or Firm* — Tracy M. Heims; Apex Juris, PLLC.(57) **CLAIM**

The ornamental design for an autonomous mobile platform, as shown and described.

DESCRIPTION

FIG. 1 is a side view of a autonomous mobile platform.
 FIG. 2 is a front view of a autonomous mobile platform.
 FIG. 3 is a back view of a autonomous mobile platform.
 FIG. 4 is a top view of a autonomous mobile platform.
 FIG. 5 is a bottom view of a autonomous mobile platform.
 FIG. 6 is an elevated perspective view from the rear of a autonomous mobile platform.
 FIG. 7 is an elevated perspective view from the front of a autonomous mobile platform.

FIG. 8 is a side view of a autonomous mobile platform shown with an attachment; and,

FIG. 9 is an elevated perspective view from the rear of a autonomous mobile platform shown in condition of use with an attachment including a tow bar and cart.

In the drawings, the broken lines depict an attachment including a tow bar and cart which form no part of the claimed design.

1 Claim, 9 Drawing Sheets(56)
